UNITED STATES PATENT OFFICE.

GREENLEAF WHITTIER PICKARD, OF NEWTON CENTER, MASSACHUSETTS, ASSIGNEE
TO WIRELESS SPECIALTY APPARATUS COMPANY, OF BOSTON, MASSACHUSETTS, A
CORPORATION OF NEW YORK.

RADIO APPARATUS.

Application filed September 29, 1923. Serial No. 665,528.

This invention relates to radio apparatus more particularly of the type wherein the form of receiving apparatus, substantially all the devices are enclosed in and attached to a 5 box or cabinet N having terminals, binding posts or connecting points for the connection of aerial conductors which intercept the transmitted waves.

The object of the invention is to provide 10 such a receiving set with means convenient to the purchaser and user for operating the set by various aerials.

The invention consists of the improvements 15 described and pointed out in the claims below, and shown in the drawings, which are diagrammatic and of which

Figure 1 is an illustration of one embodiment of the invention;

Fig. 2 is an illustration of another embodiment; and

Fig. 3 is an illustration of a preferred embodiment.

The invention in its preferred form is designed to permit the user of the receiving set 25 to use either a small or a large grounded antenna of the Marconi type (Reissue Patent 11,913) without change of calibration of the antenna tuning condenser, and to permit the user to employ at will with his receiving set 30 either of the now well-known forms of aerials, i. e., the grounded antenna of said Marconi type or the ungrounded closed loop or coil aerial of my Patent 876,996, without change 35 of tuning condenser; that is, permitting the use of the same tuning condenser for either type of aerial.

In Fig. 1, the dot and dash rectangle represents a cabinet N enclosing the apparatus with the exception of the aerials, the cabinet 40 carrying connecting points or binding posts A¹, A² for a grounded Marconi aerial AE, and connecting points or binding posts L¹, L² for my closed ungrounded condenser-tuned loop aerial L.

The common tuning condenser for these 45 aerial systems of different types is at C shown as associated in a common fashion with the local receiving apparatus, including a thermionic tube or other detector U and a transformer R, which couples said tube with a receiving telephone or additional amplifying tubes. The grounded aerial or antenna system, with which variable tuning condenser 50 C is associated, is shown in preferred form,

wherein condenser C forms a part of the 55 closed circuit tuned by it and including the adjustable secondary coil of an oscillation transformer T, the primary and secondary of which have a variable coupling, the two coils constituting a coupling between the closed 60 circuit of condenser C and the open grounded circuit of the antenna A—E; and in the antenna circuit is preferably a variable tuning condenser AC. The portion of the antenna to the right of binding posts A¹, A², and including condenser AC and the primary of transformer T, forms a part of the receiving set itself inside cabinet N; and to binding posts A¹, A² is connected any desired grounded 65 open or Marconi antenna A—E. From loop binding posts L¹ a lead 20 is taken to a switch point 2; and from loop binding post L² is taken a lead 10 to one side of tuning condenser C. A switch S is connected via a lead 70 30 to the other side of condenser C. In the position of switch S shown in full lines, contacting with switch point 2, the variable condenser C is connected in the circuit of the loop to which terminals L¹, L² are adapted to be connected, so that condenser C may serve 75 as the necessary tuning condenser for the loop, as explained in my said patent. One end of the secondary of transformer T is connected to a second switch point 1 of switch S; and in the position of switch S shown in dotted lines, contacting with switch point 1, condenser C is included in the secondary circuit 80 of antenna A—E, so that the user may employ 85 this same condenser not only to tune the loop, but to tune the antenna secondary. While it 90 is possible, and sometimes practicable, to have both antenna A—E and loop aerial L simultaneously connected to their respective binding posts on the receiving cabinet N, yet if the antenna A—E which happens to be employed is of substantial size and also the loop L which happens to be employed is not of the most efficient design, it will be better in practice to disconnect the top A of the antenna 95 from binding post A¹ when switch S is moved to the full line position shown. This will ensure against interference by undesired signals with the reception to be obtained by way of loop L, which interference otherwise might affect the receiving apparatus U, R, etc., by 100 way of transformer T and by way of the various electrostatic couplings, even including 105 the portion of the antenna secondary circuit

105

opened by switch S. By such an arrangement as the above it is made possible for the user to employ at will, with the same tuning condenser, either type of aerial, which is very desirable. For the purpose of receiving communications from long distance, he may prefer to use the grounded antenna. But he may prefer to use the loop aerial, either in cases where it is not practicable to provide a grounded antenna, or also for the purpose of assisting in cutting out interference by taking advantage of the directional properties of the loop aerial.

In Fig. 2 is a modified form of apparatus 15 in and on the cabinet N indicated by the dotted line closed rectangle. Here both the antenna A—E and the loop L are connected to the binding posts AL¹ and AL² on the cabinet. The transformer is indicated as a 20 single coil or auto transformer AT. Two switches S¹, S² are shown, operating on a common contact 3 and upon a plurality of, switch points, as shown, connected to taps along the transformer coil. The common 25 tuning condenser C is shown as having one side connected to switch S² and the other to binding post AL², and both sides connected to the receiving thermionic tube U which is connected to the head telephones P. When 30 both switches S¹ and S² are closed to contact 3, as shown in dotted lines, condenser C is operatively connected in the circuit of loop L, the antenna coupling coil AT being cut out of circuit. While the upper part A of 35 the antenna may be left connected to post AL¹ while loop L is so connected, yet if the grounded antenna have greater receiving effect than loop L, such as to enable its effect to swamp the effect of the loop, then the antenna lead-in should be removed from post 40 AL¹ when the loop is in action. When switch S¹ is open to contact 3 and connected to the switch points leading to coil AT, the apparatus is in condition for normal operation by 45 the antenna A—E via coupling coil AT to the closed circuit AT, C, which closed circuit is tunable by condenser C and by the operation of switches S¹, S² over the transformer switch points. In this case, switch S² also is 50 moved to connect with the transformer switch points, both switches being in contact with various of the transformer switch points as illustrated in full lines, and disconnected from common switch contact 3. In this condition of the apparatus, coil AT acts as the 55 coupling coil for antenna A—E, and condenser C acts as the critical tuning element of the secondary circuit including transformer AT. In the form of Fig. 2, it is better 60 to disconnect loop L from binding posts AL¹ and AL², if it affords a deleterious inductance in shunt to the antenna tuning coil AT.

Fig. 3 illustrates a modified embodiment 65 of the apparatus in and on the cabinet N shown in dotted lines. In this form, the

grounded antenna AE and the loop or coil aerial L both may be left attached to the aerial terminals of the set, and the antenna A—E may be either a small indoor grounded antenna or a large outdoor grounded antenna. As in Fig. 1, the antenna is connected to the terminals A¹, A² of the set, and the loop aerial L is connected to terminals L¹, L² thereof. Also variable tuning condenser C can be connected in either the secondary of 75 the grounded antenna system or in the loop aerial system L, at will. As in Fig. 1, the coupling between the grounded antenna and its secondary circuit consists of an inductive transformer T, the variable antenna tuning 80 condenser AC being in series with the primary coil of this coupling. Switch S controls condenser C as to including it at will in either the antenna system or the loop system. Across antenna terminals A¹, A², a condenser 85 K is arranged to be connected by a switch W operating on contact point A³. As is well known, the variable antenna tuning condenser AC is calibrated as a matter of convenience to the user to assist him in adjusting 90 the set to receive from desired distant transmitters by adjusting the condenser to a point on the scale known to him to give reception from such transmitter. Condenser K has a value in capacity which is equal to the difference of the capacity of a large and small grounded antenna. The user may desire to employ a small indoor grounded antenna (.001 mfd.) or a large outdoor grounded antenna (.003 mfd.) for the same wave length 95 range; although antenna tuning condenser AC usually is calibrated to correspond with the capacity of the ordinary outdoor grounded antenna of dimensions for receiving from entertainment-broadcasting transmitters. When switch W is closed to contact A³, a condenser K of the above specified capacity (which in a fraction of a microfarad may be .002) thereby is placed in shunt to condenser 100 AC and the primary of transformer T, and a small indoor grounded antenna may be employed with the condenser AC calibrated relative to the usual large outdoor grounded antenna. Thus condenser K of such value, and switch W permit use of a small indoor 105 grounded antenna for the same wave length as a large outdoor grounded antenna, without any change of calibration of antenna condenser AC relative to the large antenna. Switch S preferably carries three contacting 110 knife switch blades X, Y and Z, switch S being preferably a triple pole, double throw device. The change of variable tuning condenser C from an antenna system tuning condenser to a loop system tuning condenser is 115 made by the operation of the switch blade Y from the full line position shown (connecting switch points 3 and 4) to the dotted line position connecting switch points 3 and 7. Switch S may comprise such switch blade Y 120

alone, as shown in Fig. 1, in which case, however, the lead-in of the antenna preferably is removed when loop system L is in service. Preferably, however, even if the lead-in of the antenna be removed when the loop is in service, switch S should include blade Z which serves to connect the other side of condenser C (from that connected by blade Y) to the antenna secondary and the loop system respectively. Also, switch S preferably comprises, in addition to blades Y and/or Z, the blade X arranged with the contact points 1 and 2 to cut out antenna lead-in when condenser C is disconnected from the antenna secondary and connected to the loop system, and to cut in the antenna when condenser C is connected in the closed secondary with the coil of coupling transformer T. It is not necessary to have all four binding posts A¹, 20 A², L¹, L², for clearly L² may be combined with A².

As a rule, the antenna lead-in, the wire leading from binding post A² to earth E, and the loop aerial from L to binding posts L¹, L² 25 are not furnished with the apparatus as sold, which includes only the cabinet N and the local apparatus shown as located therein.

Tuning condenser C preferably possesses a sufficient range of capacity to tune each of 30 the secondary circuit of antenna A—E and the loop aerial L to the desired wave lengths; and preferably it has substantially the same wave length range for said two aerials.

Among the advantages of the invention are 35 avoiding the necessity of duplicating variable condenser C for both the antenna secondary circuit and the loop system; the convenience to the user of being able readily to shift from an antenna aerial A—E to a loop aerial L; and the ability to employ different-sized 40 grounded antenna A—E (by the provision of condenser K and switch W) without changing the calibration of the antenna condenser AC and without the necessity of using 45 a differently calibrated antenna condenser when such different grounded antenna is used.

I claim:—

1. In a radio communication apparatus, 50 the combination with two independently operating aerials, one of the grounded antenna type and the other of the ungrounded closed loop aerial type, the antenna aerial having a closed tuned associated circuit; of 55 a variable tuning condenser; and switching means for inserting said condenser alternately at will in the closed associated circuit and in the closed loop aerial.

2. In a radio receiving apparatus, the combination with a variable tuning condenser, 60 of a closed secondary circuit tunable thereby; connecting points for a grounded antenna and for an ungrounded closed loop aerial; means for coupling the secondary circuit with a grounded open antenna con-

nected to said points; and a switch which in one position closes the antenna circuit, closes the secondary circuit through the condenser and open-circuits the loop, and in another position opens the antenna and the secondary circuit and closes the loop circuit through the condenser. 70

3. Radio-receiving apparatus which comprises an antenna aerial and a loop aerial constructed to operate independently thereof, an oscillation transformer; a secondary circuit of the antenna-aerial constructed as a resonant circuit and including a variable condenser having substantially the same wave-length range for the antenna aerial as 80 for the loop aerial; and a switch constructed and arranged to open said secondary circuit and connect the loop aerial in parallel with said condenser, and alternately to disconnect the loop-aerial from the condenser and 85 include the condenser in the secondary circuit of the antenna-aerial.

4. Radio-receiving apparatus which comprises antenna-aerial terminals and loop-aerial terminals, an oscillation transformer 90 connected to the antenna terminals; a secondary circuit of said antenna-aerial constructed as a resonant circuit and including a variable tuning condenser having a sufficient range of capacity to tune either said 95 secondary circuit or the loop aerial to desired wave-lengths; a lead from one loop-terminal to one side of said condenser; a second lead from the other loop-terminal to a switch point; and a switch constructed and 100 arranged to open said secondary circuit and connect said switch-point of said second loop lead to the other side of said condenser, and alternately to disconnect said switch-point from the condenser and close the secondary circuit through the condenser. 105

5. Radio receiving-apparatus which comprises antenna-aerial terminals and loop-aerial terminals; a closed resonant circuit including a variable condenser having a range 110 of capacity sufficient to tune either said secondary circuit or a loop-aerial to desired wave-lengths; an oscillation transformer coupling said antenna-aerial terminals to said closed resonant circuit; and switching 115 means constructed and arranged to open said closed resonant circuit and connect the loop aerial in parallel with said condenser, and alternately to open the loop circuit and include the condenser in the secondary circuit 120 of the antenna-aerial.

6. Radio receiving-apparatus which comprises local receiving apparatus; a closed circuit connected to the receiving apparatus; independently operative antenna and loop aerials; a condenser associated co-operatively with said closed circuit and having a capacity suitable to make the antenna and loop aerials respectively resonant to a desired order of wave lengths; and switching 130

means for alternately connecting the antenna aerial and the loop aerial to said condenser, whereby either aerial system at will is made resonant to the desired order of 5 wave-lengths.

7. Radio receiving apparatus including, in combination, the aerial apparatus and a receiving set, the aerial apparatus including a grounded antenna circuit and a closed loop 10 aerial circuit, said antenna circuit and loop aerial circuit being severally complete and functionally independent of each other, and the receiving set including binding posts for the antenna circuit and the loop aerial cir-

cuit together with switching means for oper- 15 atively connecting the receiving set at will with either the loop circuit or the antenna circuit.

8. Radio receiving apparatus, including, in combination, a receiving set and asso- 20 ciated antenna and loop circuits; a variable tuning condenser in the receiving set together with connecting points for the antenna circuit and the loop circuit; and switching means for including said tuning 25 condenser effectively in the circuit of the antenna and the loop alternately at will.

GREENLEAF WHITTIER PICKARD.
